UNITED STATES PATENT OFFICE.

JACOB WINTRODE, OF HUNTINGTON, AND HORACE G. SOLOMON, OF HOPE,
INDIANA.

FENCE.

SPECIFICATION forming part of Letters Patent No. 224,501, dated February 10, 1880.

Application filed September 12, 1879.

To all whom it may concern:

Be it known that we, JACOB WINTRODE, of Huntington, in the county of Huntington and State of Indiana, and HORACE G. SOLOMON, of Hope, in the county of Bartholomew and State of Indiana, have invented certain new and useful Improvements in Fences; and we do hereby declare the following to be a full, clear, and exact description thereof, reference 10 being had to the accompanying drawings, and to the letters of reference marked thereon.

The nature of our invention consists in the construction and arrangement of a fence, as will be hereinafter more fully set forth.

15 In order to enable others skilled in the art to which our invention appertains to make and use the same, we will now proceed to describe its construction and operation, referring to the annexed drawings, in which—

20 Figure 1 is a perspective view, showing the construction of our fence. Fig. 2 is an end view of the same.

Each panel of our fence is composed of a series of horizontal rails, A A, connected at or 25 near their ends by upright cleats or boards B B. At one end of each panel the upright B is at the ends of the horizontal rails, while at the other end two or more of the rails project beyond the upright, as shown in the drawings, 30 so that when two adjacent panels overlap each other there will be an upright on one side only at the joint. The thus overlapping ends of the two panels rest on a block or base, C, and a stake, D, is driven down on each side 35 into the ground, so as to hold the base in position. The relative dimensions of the base with the overlapping panels are such that the stakes D will have their upper ends bearing against the upright B on one side and the bottom rail on the other side, and thus prevent 40 any lateral movement of the panels at their lower ends at the same time, as said stakes hold the base in place.

The upper ends of the overlapping panels are held by two stakes, F F, which are driven 45 into the ground, one on each side of the fence, said stakes crossing each other above the fence, and bear against the upper ends of the upright and top rail, as shown. A top rail, I, is then laid in the crotches of the stakes F, which 50 rail may be nailed to said stakes and bind them firmly on the two panels.

A wire, a, is passed and tied in any suitable manner around the stakes F, immediately under the upper rails of the panels, so as to 55 still further bind the parts together. This wire also acts in such a manner that if the lower end of either stake should rot the fence would yet be held firmly in place.

This fence is cheap, easily built, and at the 60 same time firm and durable.

We are aware that fences have been made with two long stakes crossing each other and supporting a top rail, and connected near their lower ends by a brace, upon which brace the 65 panels are supported, and we do not claim such as our invention. Neither do we claim, broadly, to support the panels on a base-block.

Having thus fully described our invention, what we claim as new, and desire to secure by 70 Letters Patent, is—

In a fence, the panels A B A B, constructed as described, and overlapping each other, resting upon a base, C, and held in position by the short stakes D D, in combination with the long 75 crossed stakes F F, binding and supporting wire a, and the top rail I, all substantially as and for the purposes herein set forth.

JACOB WINTRODE.
H. G. SOLOMON.
